UNITED STATES PATENT OFFICE.

CHARLES D. FULLER, OF LATROBE, PENNSYLVANIA, ASSIGNOR OF FORTY PER CENT.
TO A. S. HENRY, OF NEW YORK, N. Y.

FURNACE.

1,356,859.

Specification of Letters Patent. Patented Oct. 26, 1920

Application filed June 2, 1920. Serial No. 385,962.

To all whom it may concern:

Be it known that I, CHARLES D. FULLER,
a citizen of the United States, residing at
Latrobe, in the county of Westmoreland,
5 and State of Pennsylvania, have invented
new and useful Improvements in Furnaces,
of which the following is a specification.

The invention relates to improvements in furnaces and analogous structures.

- 10 The object of the present invention is to improve the construction of furnaces and analogous constructions having passages for gases either before or after combustion and to provide a simple, practical and efficient construction adapted to control the speed, direction and action of gases in passing through such passages whereby the gases may be caused to travel in the desired direction at the proper speed and without 15 20 a swirling or rotary motion thereby preventing the injury to passage walls resulting from the passage therethrough of uncontrolled gases of this character.

With these and other objects in view the invention consists in the novel construction, combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention:

In the drawing in which like characters of reference designate corresponding parts in the several figures:

Figure 1 is a vertical sectional view through a portion of one side of a reversible open-hearth furnace.

Fig. 2 is a vertical transverse sectional view on the line 2-2 of Fig. 1.

Fig. 3 is a sectional view on the line 3—3
45 of Fig. 1.

Fig. 4 is a vertical sectional view of a portion of a furnace showing a passage provided with vertical and horizontal grooves.

Fig. 5 is a similar view showing the furnace provided with vertical and inclined or diagonal grooves.

Fig. 6 is a vertical sectional view of a portion of a furnace showing longitudinal oppositely inclined and horizontal or transverse grooves.

Referring to the drawing in which the improvements are shown applied to a reversible open-hearth furnace of standard type, 1 designates the vertical passage which alternately forms the uptake and downtake at one side of the open-hearth furnace and the said passage 1 is connected at the top with an inclined passage 2 extending downwardly and transversely of the furnace over the bridge wall 3 for directing the gases or fuel elements into the furnace body 4 for ignition over the bath thereof in the usual manner. The side walls of the vertical passage 1 is provided with vertical grooves 5 and the arched top wall 6 has horizontal grooves 7 in the concave inner or lower face thereof. The side and top walls of the bridge wall passage 2 are provided with grooves 8 and 9 while the bridge wall has grooves 10. The front and rear and top walls of the furnace body are provided with horizontal grooves 11 and 12. The grooves of the side walls of the passage 1 are vertical while the grooves of the bridge wall passage are inclined. The grooves of the top wall 6 and the walls of the furnace body are horizontal. These grooves extend in the direction of the flow or travel of the gases or elements of combustion and they are shown in the form of flutes but they may consist of corrugations or angular channels and they are adapted to prevent the swirling or rotary action of gases or fuel elements or gaseous products of combustion and the injury resulting from the uncontrolled action of hot gases and products of combustion. Also as illustrated in Fig. 4 of the drawing horizontal grooves 13 may be employed. These grooves intersect the vertical grooves 5 and operate to check or retard the flow of the gases and thereby reduce the speed of the same to enable the speed of the gases to be regulated to the extent of preventing a too rapid passage of the gases through the furnace passages. This will facilitate a more uniform mixing of the fuel elements and enable the appropriate proportions of the same to be more accurately controlled. Also this checking or reduction of the speed of the gases will enable portions of a furnace to be subjected for a greater length of time to the action of the hot gases than would otherwise be possible, thereby utilizing the heat of the gases to a maximum degree.

Furthermore as illustrated in Fig. 5 of the drawings the vertical or horizontal grooves 5 may be interrupted by inclined or diagonal grooves 14. This will effect a reduction of speed but will not check the gases to the same extent as horizontal or transverse grooves and as illustrated in Fig. 6 the inclined or diagonal grooves 15 may be oppositely inclined and horizontal grooves 16 10 may also be employed.

The grooves not only enable the speed and the direction of the gases to be controlled or regulated but they also greatly increase the area of the interior surface of the 15 passages and enable the heat to be distributed over a greater area than plain walls of a passage of similar dimensions and this increase in the interior surface and the resultant spreading of the heat lessens the 20 heating of the exterior of the furnace walls and the temperature of the walls at the exterior is much less than where the walls are not provided with the grooves. This will reduce to a minimum injury to the walls 25 from expansion and cooling stresses and with the removal of the injury due to the spiral or swirling action of uncontrolled gases passing through passages the durability 30 of the walls of the passages and analogous furnace structures will be materially increased.

While the improvements are shown applied to an open hearth furnace in the accompanying drawings it will be readily apparent that they are applicable to various structures having passages through which gaseous fuel elements or gaseous products of combustion pass and the durability of stacks 35 will be materially increased by eliminating the swirling action of the smoke and other gases and by increasing the interior surface 40 area by means of the said grooves of the channels.

What is claimed is:

45 1. A furnace structure or the like, having a wall or passage provided with grooves adapted to increase the interior surface of the passage and arranged to prevent swirling or rotary movement of the gases traveling through the passage.

50 2. A furnace structure or the like, having a wall or passage provided with grooves adapted to increase the interior surface of the passage and arranged to prevent swirling or rotary movement of the gases traveling through the passage, said grooves being disposed longitudinally of the passage.

55 3. A furnace structure or the like, having

a wall or passage provided with grooves adapted to increase the interior surface of 60 the passage and arranged to prevent swirling or rotary movement of the gases traveling through the passage, said grooves extending longitudinally and transversely of the passage.

4. A furnace structure or the like, having a wall or passage provided with grooves adapted to increase the interior surface of the passage and arranged to prevent swirling or rotary movement of the gases traveling 70 through the passage, said grooves extending longitudinally and also diagonally of the passage.

5. A furnace structure or the like, having a wall or passage provided with grooves 75 adapted to increase the interior surface of the passage and arranged to prevent swirling or rotary movement of the gases traveling through the passage, said grooves being disposed longitudinally of the passage and 80 also diagonally in opposite directions.

6. A furnace structure or the like, having a wall or passage provided with grooves adapted to increase the interior surface of the passage and arranged to prevent swirling 85 or rotary movement of the gases traveling through the passage, said grooves extending diagonally of the passage in opposite directions.

7. A furnace structure or the like having 90 a wall or passage provided with transverse grooves adapted to increase the interior surface of the wall or passage and arranged to affect the passage of gases for controlling the same.

8. A furnace structure or the like, having a wall or passage provided with grooves adapted to increase the interior surface of the passage and arranged to prevent swirling or rotary movement of the gases traveling 100 through the passage, said grooves extending longitudinally of the wall or passage and also diagonally of the same in opposite directions and transversely of the wall or passage at right angles to the longitudinal 105 grooves.

9. A furnace structure or the like having a wall or passage provided with grooves extending in the general direction of the travel of the gases through the furnace and 110 adapted to prevent swirling or rotary movement of the gases.

In testimony whereof I have hereunto set my hand.

CHARLES D. FULLER.
